UNITED STATES PATENT OFFICE

124,515

DESIGN FOR AN EVENING GOWN ENSEMBLE

Vera E. Jacobs, New York, N. Y.

Application November 12, 1940, Serial No. 96,479

Term of patent 3½ years

To all whom it may concern:

Be it known that I, Vera E. Jacobs, a citizen of the United States, residing at 1016 Fifth Avenue, New York city, in the county of New York and State of New York, have invented a new, original, and ornamental Design for an Evening Gown Ensemble, of which the following is a specification, reference being had to the accompanying drawings, forming part thereof.

The jacket member, bodice, and shoulder straps are trimmed with sequins.

I claim:

The ornamental design for an evening gown ensemble, substantially as shown and described.

VERA E. JACOBS.
